UNITED STATES PATENT OFFICE.

JAMES G. PENNYCUICK, OF TORONTO, CANADA.

DESIGN FOR A PRISM-PLATE.

SPECIFICATION forming part of Design No. 27,342, dated July 13, 1897.

Application filed June 15, 1897. Serial No. 640,929. Term of patent 14 years.

To all whom it may concern:

Be it known that I, JAMES G. PENNYCUICK, a citizen of the Dominion of Canada, residing at Toronto, in the county of York and Province of Ontario, Canada, have invented and produced a certain new and useful Design for Prism-Plates, of which the following is a description.

My invention relates to designs for prism-
10 plates.

It is illustrated in the accompanying drawings, wherein—

Figure 1 is a perspective view of my improved design. Fig. 2 is a section therethrough.

Like parts are indicated by the same letter in both the figures.

A is a body of glass; B B, a series of prisms thereon. The body of glass has a substan-

tially plain or smooth surface on one side, 20 with a series of prisms on the other side. The body of glass is triangular approximately in the shape of a right-angle triangle, and the prisms are arranged substantially vertical to the hypotenuse. 25

I have shown certain angles, arrangements, and numbers of the prisms; but the essential feature of my invention is a triangular body of glass with one practically smooth side and one prism side, the prisms arranged vertically 30 to the hypotenuse.

I claim—

The design for a prism-plate substantially as shown and described.

JAMES G. PENNYCUICK.
